ATTORNEY

UNITED STATES PATENT OFFICE.

ARTHUR BRÜCHMANN, OF TYLER, MINNESOTA.

AUTOMATIC RAILWAY GATE.

Application filed November 5, 1926. Serial No. 146,302.

The main object of this invention is to provide a railroad gate suitable for use at railway crossings. The railroad gate works in an automatic manner and is used in combination with an overhead wire which forms part of a circuit for illuminating a signal lamp and actuating solenoids which automatically lower the gates at an instant when a locomotive closes the circuit thru the overhead trolley wire.

The above and other objects will become apparent in the description below, in which characters of reference refer to like-named parts in the drawing.

15 Referring briefly to the drawing, Figure 1 is a sectional elevational view, showing the railroad gates and the mechanism for actuating the same.

Figure 2 is a diagrammatic view, showing 20 the wiring diagram of the circuits used for actuating the gates and signal lamp.

Figure 3 is a view similar to Figure 1, showing the gates in raised position.

Referring in detail to the drawing, the 25 numeral 10 indicates the roadbed upon which rails 11 and 12 are seated. At a position where a vehicular road traverses the rails, pedestals 13 and 14 are mounted on opposite sides of the vehicular road, as illustrated in Figures 1 and 3. These pedestals project from the surface of a base plate 15, which latter covers a compartment 16. Ears 17 project downwardly from the base plate 15 and journal a grooved pulley 18. The 30 pedestals pivotally support gate arms 19 and 20 by studs 21 in such manner that the longer portion of these gate arms span across the vehicular road and project a short distance from the opposite side of the pivotal point. These gate arms are provided with pivoted legs 22 which support the same when said gate arms are in lowered position, as indicated in Figure 1. The shorter ends of the gate arms have one end of cables 23 and 24 attached thereto. These cables train about the grooved pulleys 18 and extend from said pulleys thru conduits 25 into a subterranean chamber 26 which is constructed beneath the vehicular road and uses a 35 pair of solenoids 27 and 28. The plungers 30 of these solenoids are pivotally connected to bars 31 and 32 intermediate their length in slots provided in said bars. These bars are pivotally anchored at their lower 40 ends between ears 33 and the upper ends of

said bars have the cables 24 and 23 attached thereto.

The gates are adapted to be simultaneously lifted and lowered and are located on opposite sides of the railroad bed so that the 60 long ends of the gate arms 19 and 20 span a vehicular roadbed which traverses a railroad bed. An overhead trolley wire 34 forms an electrical lead thru signal lamps 35 and 36 located on opposite sides of the railroad bed. This circuit has connected thereto in series, the permanent magnets solenoids 27 and 28. The latter normally retain their cores, and are wound so that they expel the cores upon energization of the solenoids. 70 The electrical connections are as follows: the lamps 35 and 36 are bridged across the rail 11 and wire 34 so that each lamp is in parallel circuit with respect to the other and the lamps are energized by the battery 39 75 through the rail and wire. The solenoids 27 and 28 on each side of the track are in series with each other and the two pairs of solenoids 27 and 28 are in parallel with each other and similarly bridged across the rail 80 11 and wire 34, through which they are energized by the battery 39. When a shoe 37 mounted on the locomotive, which is shown diagrammatically by the circle 38, contacts with a portion of the rail 11 and the overhead trolley wire 34, the circuit is closed 85 through solenoids 29 and 28 and through lamps 35 and 36, illuminating the lamps 35 and 36 and energizing the solenoids thus expelling the plungers 30, the cables 24 and 90 23 consequently being paid out, permitting the gates to be lowered. When the train has passed and becomes disengaged from the overhead trolley wire 34, which only extends a short distance, or as much as is required 95 on both sides of the vehicular crossing, the circuit is again broken and the solenoids retract the plungers 30, taking up the cables 23 and 24, thereby lifting the gate arms 19 and 20 to the raised position, as indicated in 100 Figure 3. The source of energy 39, such as a battery of cells, is located on the locomotive and as every crossing is arrived at, the lamps 35 and 36 are illuminated and the solenoids are simultaneously energized and perform their function of lowering the gates 105 until such time as the train has completely passed the crossing.

I claim:—

In a device of the class described, railroad 110

gates, pedestals pivotally supporting said gates, said gates being arranged on both sides of a railroad bed at the intersection between said railroad and a roadway, the 5 railroad bed having a subterranean chamber beneath it, levers in said chamber, solenoids actuating said levers, cables connected to said levers and gates, said cables when pulled lifting said gates, grooved rollers mounted 10 beneath said pedestals, the cables extending horizontally from the levers to the rollers and vertically from the rollers to the gates

being attached to the latter, said levers in said chamber being slotted, plungers in said solenoids engaging the slotted portion of 15 said levers, said plungers normally holding said gates in substantially vertical position, and electrical means for energizing said solenoids to expel said plungers, thereby releasing the plungers and cables and allowing 20 said gates to fall by gravity.

In testimony whereof I affixed my signature.

ARTHUR BRÜCHMANN.
